UNITED STATES PATENT OFFICE.

STUART M. FORD, OF BRIDGEPORT, CONNECTICUT, ASSIGNOR TO THE SALT'S TEXTILE MANUFACTURING COMPANY, OF BRIDGEPORT, CONNECTICUT, A CORPORATION OF CONNECTICUT.

SHUTTLE FOR LOOMS.

1,272,650.

Specification of Letters Patent. Patented July 16, 1918.

Application filed April 1, 1916. Serial No. 88,203.

To all whom it may concern:

Be it known that I, STUART M. FORD, a citizen of the United States, residing at Bridgeport, in the county of Fairfield and 5 State of Connecticut, have invented certain new and useful Improvements in Shuttles for Looms, of which the following is a specification.

My invention relates to shuttles for looms 10 and more particularly to one embodying means wherein, upon the substantial exhaustion of the weft, a circuit will be closed when the shuttle reaches its box. Said circuit may include means for setting in operation 15 a knock-off mechanism or a weft replenishing mechanism, of any approved type, or a suitable indicating mechanism, as may be desired. The invention will be understood by reference to the accompanying drawings 20 in which Figure 1 is a plan view of the shuttle box and shuttle; Fig. 2 a side elevation of the shuttle box, partly broken away to show the shuttle therein; Fig. 3 a horizontal section through one end of the shuttle 25 and shuttle box; Fig. 4 a vertical longitudinal section through a portion of the shuttle with the end of the spike in elevation; Fig. 5 a sectional view of the bobbin to illustrate the method of preliminary winding of the 30 yarn; Fig. 6 a detail of the feeler; Fig. 7 a side view of one of the contact pieces shown in Fig. 3; and Figs. 8, 9 and 10 detail views of modifications of the contact piece in the side of the shuttle box. Similar 35 reference numerals indicate similar parts in the several views.

Referring to the drawings the numeral 1 designates the side of the shuttle box, which as shown, will be at the left-hand side of 40 the loom. The box is usually made of "fiber", an insulating material, and has an inner lining 2 of conducting material. In openings at the side of the box are two contact pieces 3 and 4. These are pivoted on 45 pins 5 and are normally projected through their openings into the box by springs 6 secured thereto and to the binding posts 7 and 7'. The latter are included in a circuit 8 (see Fig. 2) which circuit may include means 50 for setting in operation a stopping mechanism, or a weft replenishing mechanism. In order to close this circuit upon the substantial exhaustion of the filling or weft, the shuttle, spike and weft holder are constructed and arranged as follows.

The shuttle 9 may be of the usual form

open at top and bottom, and comprises a spike 10 pivoted on a pin 11 set into the shuttle. The spike is held in its closed or open position by a spring 12 which bears 60 against the square head of the spike. The latter carries a yielding contact member secured to its side. In the form shown this consists of a bowed spring 13 which may be passed through an opening 14 in the spike, 65 and the ends secured thereto, so that the sides of the spring will project sufficiently to give a good frictional contact with the barrel of the weft-holder 15 which is placed over the spike. 70

By "weft-holder" I mean any device to hold filling or weft adapted to go into a shuttle, and commonly called a bobbin, cop, butt-cop, &c. In the drawings I have shown a bobbin with a metal barrel over one end of 75 which is fitted a butt 16 of wood. The butt is formed with the usual groove 17 adapted to be engaged by the clips 18 (see Fig. 3) to hold the bobbin in place. It is also formed with a circumferential groove 19 to receive 80 the initial winding of the weft 20.

Below the bobbin butt, and at the rear of the groove 19, when the bobbin is placed upon the spike, is a pin 21 set into the bottom of the shuttle and which serves as a 85 pivot for a feeler 22. In the form shown this feeler is of general U-shape made of wire and has one or more turns around its pivot pin, and is extended forwardly over the weft so that its tapered end is adapted, 90 when the weft is substantially exhausted, to bear against the metal barrel, or metal section of the barrel, of the bobbin. The base of the feeler, as shown in Fig. 6, is substantially as wide as the opening in the bottom of the shuttle, and the body thereof is gradually narrowed to a substantial point, as indicated. This form of feeler prevents entangling of the yarn as the latter is being drawn off the holder. The feeler has a 95 rearward extension 23 against which bears the end of a flat spring 24 set into the bottom of the shuttle, said spring tending to press the forward end of the feeler toward the bobbin. One end of the feeler is extended laterally at 25 (see Fig. 6) and this extension bears against the shuttle bottom and prevents the feeler moving too far into the path of the bobbin when the latter is placed on the spike. 100

Secured to the sides of the shuttle are two plates 26 and 27, so positioned that when the

shuttle is in the box they will be in engagement with the contact pieces 4 and 3 respectively, pivoted in the side of the shuttle box. The pivot pin 21 may be extended to 5 engage directly with the plate 26, and the spike pivot 11 may be extended to engage directly with the plate 27. I prefer, however, to interpose between the ends of said pins and their respective plates coiled 10 springs 28 and 29 in order to insure good contact. A pin 30 serves as a stop for the spike when it is lowered to its position in the shuttle, and stops 3' and 4' limit the movements of the pieces 3 and 4.

15 The weft is wound on the bobbin as follows: As indicated in Fig. 5 the initial winding is laid in the groove 19 until said groove is substantially filled. It is then carried forward and a number of turns 20' 20 made on the bobbin, beyond the butt, and over the surface with which the feeler will contact. The weft is then brought back to the butt of the bobbin and the winding completed in the usual way. During the drawing 25 off of the weft the flat spring 24 presses the feeler 22 against the body thereof until finally the tapered end of the feeler bears against the turns 20', indicated in Fig. 5. When that portion of the weft is drawn off 30 the tapered end of the feeler will contact with the metal portion of the bobbin, so that when the shuttle reaches its box the circuit 8 will be closed through binding post 7', pivoted contact piece 4, plate 26, spring 35 28, pivot pin 21, feeler 22, bobbin 15, yielding contact member 13, spike 10, pivot pin 11, spring 29 to plate 27, thence through pivoted contact piece 3, to binding post 7. As before stated the circuit may include an 40 electro-magnet which is adapted, when energized by the closing of the circuit, to actuate or set into operation any well-known type of stopping mechanism or weft replenishing mechanism. The amount of filling laid in 45 the groove 19 in the butt of the bobbin, is sufficient to complete at least two picks of the shuttle, so that, should the feeler contact with the bobbin barrel as the shuttle leaves the box having the contact pieces 3 and 4, 50 that and the next succeeding pick will have sufficient weft to prevent an imperfection in the fabric.

Instead of the pivoted contact pieces 3 and 4, as illustrated in Fig. 2, I may use 55 any of the forms shown in Figs. 8, 9 and 10. In Fig. 8 the contact 31 may be directly secured to the binding post and be made of spring metal adapted to move in a cut-out section of the side of the box.

60 In Fig. 9 another form 32 is shown having a bowed section which normally projects through an opening in the side of the box into the path of the shuttle.

In Fig. 10 still another form is shown comprising a bowed piece 33 adapted to be 65 moved against springs 34 mounted upon studs secured to the side of the shuttle box. When the shuttle is boxed the piece 33 will be moved so as to compress the springs 34, thus insuring good contact with the metal 70 plates 26 and 27 on the side of the shuttle.

By "exhaustion" or "substantial exhaustion" of the weft, I mean such degree of exhaustion thereof as will prevent imperfections in the fabric woven.

My invention is not restricted to all of the specific details of construction described herein. As for example, instead of the bobbin barrel being of metal, it may be made of wood with a metal section so as to insure 80 a conducting surface between the feeler and the yielding member on the spike.

What I claim and desire to secure by Letters Patent of the United States is:—

1. A shuttle comprising a spike, a weft 85 holder supported on said spike and having a groove in the butt thereof to receive the initial winding, a spring-pressed feeler carried by the shuttle and pivoted beyond the initial winding and extending forwardly 90 over the initial winding to contact with said holder upon the substantial exhaustion of the weft, and means on the shuttle and shuttle box to close a circuit through said holder and spike when such contact occurs. 95

2. A shuttle comprising a weft-holder, a spike over which said holder is placed, a feeler carried by the shuttle and adapted to bear against the weft and to contact with said holder upon the substantial exhaustion 100 of the weft, plates secured to one side of the shuttle, and arranged longitudinally thereof and movable contact pieces projecting through openings in the side of the shuttle box and adapted to be engaged by said 105 plates when the shuttle is boxed.

3. A shuttle comprising a spike, a weft holder supported on said spike, a spring-pressed feeler carried by the shuttle adapted to bear against the weft and to contact with the holder upon the substantial exhaustion 110 of the weft, said feeler being pivoted beyond the initial winding and gradually tapering to its outer end, and extending forwardly over the initial winding, and means on the shuttle and shuttle box to close the circuit through said holder and spike when such contact occurs. 115

In testimony whereof I have hereunto signed my name in the presence of two subscribing witnesses.

STUART M. FORD.
